[57] CLAIM

The ornamental design for folding portable hammock, as shown and described.

DESCRIPTION

FIG. 1 is a perspective view of a folding portable hammock showing my new design;

FIG. 2 is an end view of the folding portable hammock of FIG. 1;

FIG. 3 is a side view of the folding portable hammock of FIG. 1;

FIG. 4 is a top plan view of the folding portable hammock of FIG. 1;

FIG. 5 is a bottom plan view of the folding portable hammock of FIG. 1;

FIG. 6 is an enlarged top plan view of the folding portable hammock of FIG. 1 showing the support frame of the hammock in partially folded condition with the hammock bed removed for convenience of illustration; and,

FIG. 7 is an enlarged top plan view of the folding portable hammock of FIG. 1 showing the support frame of the hammock in fully folded condition with the hammock bed removed for convenience of illustration.

FIG. 6

FIG. 7
